UNITED STATES PATENT OFFICE.

CHARLES ALFRED RANDALL, OF HAILEYBURY, ONTARIO, CANADA.

ORE-CLASSIFIER.

1,313,734.

Specification of Letters Patent.

Patented Aug. 19, 1919.

Application filed January 31, 1916, Serial No. 75,357. Renewed January 20, 1919. Serial No. 272,165.

To all whom it may concern:

Be it known that I, CHARLES ALFRED RANDALL, a citizen of the United States of America, and resident of the town of Haileybury, 5 district of Nipissing, Province of Ontario, Dominion of Canada, have invented certain new and useful Improvements in Ore-Classifiers, of which the following is a specification.

10 The invention relates to improvements in ore classifiers as described in the present specification and shown in the accompanying drawings that form part of the same.

The invention consists essentially of the 15 novel construction and arrangement of parts whereby the discharge screen of a grinding mill is provided with a fluid means for forcing the oversize particles from said screen.

The objects of the invention are to prevent 20 the accumulation of oversize particles in the discharge screen, to facilitate the discharge and generally to provide a simple and inexpensive means for increasing the efficiency of ore classifiers.

25 In the drawings, Figure 1 is a vertical sectional view through the grinding and discharge end of an ore classifier and showing the fluid pipe arranged within the discharge screen.

30 Fig. 2 is a detail of the fluid pipe, one end of said pipe being in longitudinal section to disclose the interior.

Fig. 3 shows a modified form of screen having an enlarged outer end to facilitate 35 the discharge of the oversize particles.

Like numerals of reference indicate corresponding parts in each figure.

Referring to the drawings, 1 is the grinding chamber adapted to be rotated by suitable machinery secured to its end 2 and having the discharge end 3 terminating above the launder 4, said discharge end preferably having the outwardly flaring edges 5 to facilitate the discharge of the contents.

45 The discharge end 3 is provided with a substantially funnel shaped screen 6 having its larger end secured adjacent to the inner end of said discharge end and having its cylindrical end extending outwardly beyond the launder 4.

50 It has been found in connection with the

classifiers now in use that the oversize particles have a tendency to accumulate in the discharge end and thus retard the discharge of the finer particles and while the screen 55 does away with this to a very great extent, I find that by introducing a stream of water or other means into said screen the discharge of said oversize particles is greatly facilitated.

60 7 is a feed pipe connected at one of its ends to the source of supply and at the other end to the distributing pipe 8 extending inwardly to the extreme inner end of the screen 6 adjacent to the upper side thereof, 65 said pipe 8 being closed at its inner end by the cap 9 and having a plurality of nozzles 10 from the under side thereof projecting downwardly and obliquely in the direction of the discharge.

70 In the operation of this invention the ore is introduced into the chamber 1 through the end 2 and is thoroughly ground by its engagement with the grinding medium through the rotation of said chamber, the 75 finer particles sifting through the bottom of the screen 6 while the particles which are too large to pass through the meshes of said screen are forced outwardly through said screen by the jets of water or other fluid 80 from the pipe 8 after which they are collected for subsequent return to the grinding chamber.

In Fig. 3 a modified form of screen is shown in which the outer end 12 is also of 85 cone shape thus providing a downward incline for the passage of the oversize particles.

By this invention a means is provided for keeping the particles continually in motion 90 in their passage outwardly from the grinding chamber thus preventing any clogging or accumulation of the ore and increasing greatly the efficiency of the classifier.

What I claim is:

95 An ore classifier comprising a substantially pear-shaped casing supported from a cylindrical power driven end and terminating at the other end in a similar cylindrical neck flared outwardly at the extremity, a 100 screen rigidly secured in said neck and converging from the entrance to said neck to

the center and from there projecting beyond said neck, a launder secured under said projecting screen and receiving discharge from said neck and a stationary flushing pipe extending into said screen and having nozzles directed to the ore being screened.

Signed at Englehart, Province of Ontario,
this eighth day of January, 1916.

CHARLES ALFRED RANDALL.
